PULLDOWN CALENDAR

William F. Vernon, Newton, Iowa

Application October 21, 1940, Serial No. 362,035

3 Claims. (Cl. 40—18)

This invention relates to a combination display and information device, and while not particularly limited thereto, it is particularly adapted to a mounting by which a calendar pad or other legend card may be secured to a picture in such a manner as to be normally concealed but instantly available for examination.

It has been common practice for many years to provide framed pictures provided with small calendar pads depending from the lower edge of the frame, but to the best of the applicant's knowledge, these have always been objectionable due to the unsightly appearance of the calendar pad. This unsightly appearance of the pad may be caused by repeated handling, which causes curling of the individual calendar sheets, or by ragged edges which are exposed to view when some of these sheets are torn from the pad. Some of the prior art structures have been further objectionable since in certain cases the pads were loosely connected to the picture frame by a cord or ribbon in such a manner that the pad could tilt to one side or another and was free to twist, reverse itself or flutter in response to moving currents of air in the room.

It is, therefore, the primary object of this invention to provide a combination display and information device including a sliding connection to permit the information device to be shifted between an exposed position below the picture and a position in which the information device is concealed directly behind the picture.

A further object of the invention is to provide a sliding connection including friction means to retain the information sheet in a concealed position and limiting stops to accurately predetermine the correct exposed position and to maintain the information device in horizontal alignment with the display.

A further object of the invention is to provide a sliding connection, as described above, which is strong and durable in construction, economical in manufacture and which is not likely to become damaged by reason of repeated manipulations. The specific disclosure of the present application overcomes objections to the prior art structure by providing a horizontal slot in the calendar pad arranged to encircle a vertical tab which is preferably formed by die-cutting the rear cover sheet of the picture.

Referring now more particularly to the drawing:

Fig. 1 is a front elevational view of a com-

bination picture and calendar constructed in accordance with the principles of this invention and showing the calendar in exposed position;

Fig. 2 is a rear elevational view of the device illustrated in Fig. 1 showing the calendar in its concealed position;

Fig. 3 is an enlarged vertical sectional view taken substantially on the plane of the line 3—3 in Fig. 2.

The display device or picture chosen for the purpose of illustration of the principles of this invention consists of a base sheet 10 and a glass panel 11 between which the display sheets 12 and 13 are positioned. It will be understood, of course, that the display sheets may be of any conventional form, but it has become common practice to provide the rear display sheet 12 spaced apart from the forward display sheet 13 by a die-cut filler pad 14 in order to give an appearance of depth to the picture and also in order to provide space in which another information device, as, for example, the thermometer 15, may be positioned. If desired, the picture may be also provided with a rear cover sheet 16 and arranged in a marginal frame 17. As illustrated, the frame 17 comprises a thin metal band folded to secure the elements 10, 11, 12, 13, 14 and 16 between a front flange 18 and a rear flange 19 and tab 21 is provided to penetrate the perforation (not shown) in order to secure the frame in a position about the picture.

The information device or calendar 25 comprises a backing sheet 26 on which a plurality of calendar leaves 27 are secured as by the stitching 28. The backing sheet 26 is preferably bounded by a horizontal lower edge 31, vertical side edges 32 and 33 and inclined side edges 34 and 35 joined at their upper extremities by a horizontal top edge 36. The sheet 26 is also provided with a horizontal perforation or slot 37 located slightly above the upper extremities of the calendar pages 27. The slot 37 comprises one element of the sliding connection by which the information device 25 is supported and this slot 37 is arranged to encircle the tab 41 die-cut from the rear cover sheet 16. Preferably this die-cut comprises two vertical slits 42 and 43 joined at their upper extremities by a connecting slit 44 to define the vertical edges and top of the tab. The slits 42 and 43 are preferably terminated short of the lower edge of the rear cover sheet, as at the points 45, 46, so that as the calendar backing sheet 26 is lowered into the exposed position illustrated in Fig.

1, the upper surfaces of the horizontal slot 31 will come to a positive stop against the lower extremities of the slits 42 and 43 to limit the downward movement of the calendar. It will be appreciated that when this occurs, the calendar will be securely held in perfect horizontal alignment with the picture, since the points 45 and 46 constitute two spaced-apart limit stops and will prevent any angular shifting of the calendar with respect to the picture.

The upper end of the tab 41 is preferably secured in position by a wire staple 47 arranged to hold the upper end of the tab 41 in clinching engagement with the back sheet 10. The staple 47 may be so positioned as to limit the upward movement of the calendar so that when the calendar is manually raised to conceal its position, its motion may be arrested immediately after the lower edge of the calendar pad moves above the lower edge of the picture.

When in this position it will be appreciated that the calendar is available for immediate examination by simply reaching behind the picture frame and drawing the backing sheet 26 downwardly, but unless some effort is applied to the backing sheet, the calendar will remain in raised position, since the portion of the sheet above the slot 47 is in frictional engagement between the inner surface of the tab 41 and the rear surface of the backing sheet 10. It will be noted by an examination of Fig. 3 that since the backing sheet 10 and the tab 41 are clinched together by the staple 47, these two thicknesses of material are caused to converge and form tapered wedging surfaces at the point 48. Thus, as the upper edge 36 of the sheet 26 approaches the staple 47, it will be engaged by the tapered surfaces at 48 to afford an increased frictional connection effective to maintain the calendar in raised position.

The frictional action of the structure at this point is supplemental to the friction exerted near the upper end of the inclined edges 34 and 35 at the point where these edges intersect the vertical slits 42 and 43, respectively.

It will be appreciated that since the tab 41 is die-cut from the backing sheet 16 and is secured in the same plane as the sheet 16 at both the top and bottom extremities, it will flex slightly in the intermediate portion and will thus effect a small shearing action applying a small amount of friction at the points 51 and 52. In this connection it may be pointed out that a similar frictional resistance is applied as the calendar is moved to its completely exposed position, for at this time the upper edge of the slot 31 approaches the lower end of the slits 42 and 43, and since the surfaces of the cover sheet 16 and the tab 41 diverge from the same plane at the lower extremity of the sheet, these surfaces will converge to constitute tapered wedging surfaces in frictional engagement with the backing sheet 26 of the calendar.

From the above description it will be seen that while the calendar pad is completely concealed in its raised position, it is quite readily available for inspection, since practically its entire surface is exposed on the rear of the picture frame where it may be conveniently reached and drawn into the exposed position. This, of course, eliminates the necessity of any ribbons or auxiliary means to draw the calendar from its concealed location. It will also be seen that when the calendar is in raised position, it is held against accidental displacement by a frictional action of the

tapered wedging surfaces and when lowered to the exposed position, it is positively stopped in exact horizontal alignment by means of the spaced-apart limit stops at 45 and 46 and is further frictionally secured by the wedging action exerted on the upper edge of the slot 31 as this slot approached the lower extremities of the slits 42 and 43. It is appreciated, of course, that the tab 41 may be made of any width desired although it has been illustrated as relatively wide in order that the inclined side edges 34 and 35 may extend under the tab. This feature provides convenience in packing since the assembled pictures may be slid into paper cartons, etc., without danger of having the edges of the calendar catch and tear on the edges of the carton.

In practice it has been found preferable to form the tab 41 in the manner shown, but it may be pointed out that an equivalent structure may 20 be constructed by reversing the tab so that it is integral with the cover sheet at its upper end and otherwise secured at its lower end.

Having thus described my invention, I claim:

1. A display device of the character described comprising a display element and an information element in slidable engagement therewith, the display element comprising a base sheet, a rear cover sheet superimposed on the rear surface of said base sheet including a pair of spaced-apart vertical slits joined at their upper extremities by a connecting slit, the lower extremities of each of said vertical slits terminating short of the lower edge of the rear cover sheet to provide a pair of spaced-apart stops for the aforementioned information element; the cover sheet including a vertical tab defined by said slits, anchor means near the upper end of said tab comprising a staple securing the tab to the base sheet in face-to-face relation to provide tapered wedging surfaces to secure the information element at the upper end of the tab; the information element comprising a sheet having a horizontal slot in said sheet encircling the aforementioned tab to secure the information element in sliding relationship with respect to the base sheet, the edges of the information element including a free horizontal lower edge, free vertical side edges adjoining said lower edge, and a top edge joined by inclined edges extending under the surface of the tab.

2. A display device of the character described comprising a display element and an information element in slidable engagement therewith, the display element comprising a base sheet, a vertical tab, anchor means near the upper end of said tab securing the tab to the base sheet, tapered wedging surfaces to secure the information element at the upper end of the tab; the information element comprising a sheet having a horizontal slot in said sheet encircling the aforementioned tab to secure the information element in sliding relationship with respect to the base sheet, and additional anchor means adjacent the lower end of the tab to secure the tab to the base sheet and to limit the downward sliding movement of the information element.

3. A display device of the character described comprising a display element and an information element in slidable engagement therewith, the display element comprising a base sheet, a rear cover sheet superimposed on the rear surface of said base sheet and including a pair of spaced-apart vertical slits, a pair of spaced-apart stops for the aforementioned information element adjacent the lower ends of said slits, the cover

sheet including a vertical tab defined by said slits, anchor means for said tab securing the tab to the base sheet in face-to-face relation to provide tapered wedging surfaces to secure the information element at the upper end of the tab; the information element comprising a sheet having a horizontal slot in said sheet encircling the aforementioned tab to secure the information

element in sliding relationship with respect to the base sheet, the edges of the information element including a free horizontal lower edge, free vertical side edges adjoining said lower edge, and a top edge joined by inclined edges extending under the surface of the tab.

WILLIAM F. VERNON.
